TRAY CONSTRUCTION

Harry E. James, Atlantic City, N. J., and William J. McClintock, Jr., Harrisburg, Pa., assignors to James, Inc., Atlantic City, N. J., a corporation of New Jersey

Application October 5, 1934, Serial No. 747,064

19 Claims. (Cl. 229—42)

This invention relates to a tray construction, and more particularly, to a partitioning tray for use with candy boxes and the like, and adapted to divide the interior thereof into a plurality of compartments.

It is an object of the invention to provide a tray of this type which is characterized by sturdiness, simplicity of construction, ease of assembly, and pleasing appearance.

10 An advantageous feature of the partitioning tray made in accordance with the present invention is that the partitioning members which divide the tray into a plurality of compartments are of uniform and substantial dimensions, whereby the tray unit as a whole gives a heavy, solid and substantial effect. Another advantage resulting from the construction of the tray of my invention is that the tray may be placed in and removed from a candy box as a unit, without any 15 danger of the several parts of the tray becoming loosened or disassembled.

Other objects and advantages of the invention will become apparent after a consideration of the following description, taken in connection with 20 the accompanying drawings. In the drawings a plurality of illustrative embodiments of the invention are shown, but it must be understood that the drawings are illustrative only, and are not to be considered restrictive of the invention, since many modifications and changes in detail 25 will suggest themselves to one skilled in the art.

In the drawings:

Figure 1 is a plan view of a blank which may be used to form one of the elements of the tray.

35 Figure 2 is a perspective view showing the several elements of the tray in partially assembled position.

Figure 3 is a diagrammatic view of a candy box, top, and two trays, showing the relative positions 40 of the parts when assembled.

Figure 4 is a transverse sectional view of a candy box having two of the improved trays positioned therein.

Figure 5 is a plan view of a blank which is 45 adapted to be used to form one of the partitioning elements of the tray.

Figure 6 is a fragmentary longitudinal sectional view through the assembled tray.

Figure 7 is a fragmentary plan view, similar 50 to Figure 1, but showing a modified form of blank.

Figure 8 is a longitudinally sectional view similar to Figure 6, but showing the modified form of tray when the blank of Figure 7 is used.

Figure 9 is a perspective, assembled view of another modified form of tray.

A partitioning tray in accordance with the present invention comprises a sheet of thin cardboard or other sheet material 10 stamped in substantially the form shown in Figure 1. The corners 11 are preferably cut away, substantially as indicated, for purposes to be described below. A plurality of substantially rectangular aligned apertures 12—17, 12a—17a etc. are cut in the blank, and these apertures are positioned in a definite relation to certain longitudinal, parallel fold lines 10 formed on the sheet. The fold lines may take the form of scores or cuts extending part way through the thickness of the sheet from the upper surface downwardly, or they may be in the form of perforated lines, which may be made by the use of a 15 printer's perforating rule. Such perforations are in the form of aligned, spaced slits extending through the body of the sheet. In some cases one kind of scoring may be used to the exclusion of another, whereas in other cases the different types 20 may be used in combination, as indicated in Fig. 1. It has been found desirable to make the lines 18, 29 in the form of continuous cuts extending part way through the sheet, and the lines 21, 22 in the form of a perforated rule, particularly 25 when the sheet material being used is tinfoil-coated cardboard.

The blank of Figure 1 is folded along the several score lines to provide a plurality of upstanding, parallel, longitudinal ribs which are of substantially rectangular, inverted U-shaped cross-section. These ribs, as indicated in Figure 2 are adapted to form longitudinal partitioning members 23, 24 and side members 25, 26. Each rib comprises side walls 23a, 23b, 25a, 25b, etc., 30 and top walls 23c, 25c, etc. These walls are formed from the elongated sections between the fold lines on the sheet 10.

The apertures 12—17, 12a—17a, etc., of the several sets will be found to be in alignment with each other, and it should be noted that the apertures are formed on both side faces of the longitudinal partitioning members, but only in the inner faces 25a, 26a of the side members. It should be noted further that the longitudinal 45 members have substantial thickness and height and give a rugged appearance.

The flat portions 27, 28, 29 of the blank, between the upwardly folded ribs, are adapted to form tray bottom panels, and these elongated 50 strips are divided into substantially square compartments by the transverse partition members now to be described.

A blank 30 of substantially the form shown in Figure 5 may be stamped from a sheet of 55

cardboard or the like. Preferably it is provided with the fold lines in the form of scores or rules 31. Also slits 32, 33 may be cut entirely through the sheet material, extending substantially from the fold lines to a point adjacent the edge of the blank, as indicated. Preferably, though not necessarily, one end of the blank is beveled back as indicated at 34. When a plurality of blanks of this form have been folded along the lines 10 30, 31, they form channel-section cross members which may be threaded through the apertures 12, etc., in the blank 10. The bevelled end 34 forms a kind of point and facilitates entry of the cross members through the holes. After the 15 several cross bars have been put in place, in accordance with the method illustrated diagrammatically in Figure 2, the end tabs 32a and 33a defined by slits 32, 33, may be projected outwardly to serve as abutment means to prevent 20 accidental withdrawal of the members through the apertures. In some cases, the slits 32, 33 may extend out to and intersect the edge of the blank, but in the preferred form they terminate a slight distance short of the edge, thus leaving 25 short connecting portions 32b, 33b, which must be torn through when the tabs are projected outwardly to operative position. Such a construction prevents the tabs from interfering with the initial threading of the cross members 30 through the aligned apertures in the longitudinal bars.

It should be noted that the tongues or tabs 32a, 33a, are disposed in operative position adjacent the outer surface of the inner vertical 35 faces 25a, 26a of the longitudinal side bars 25, 26. The outer vertical faces 25b, 26b are imperforate.

The transverse partition members are of substantially the same height and thickness as the 40 longitudinal members, and when the parts are assembled, the tray as a whole presents an appearance of strength and rigidity, because all of the parts are of substantial and heavy proportions.

45 In the event that the fold lines 31, 34 are in the form of continuous scores or cuts extending nearly through the sheet so as to give a sharp corner, as is desired in some cases, such as when a foil-coated sheet is used, it is advantageous to 50 provide means for preventing the legs or sides 35, 36 of the cross bars from collapsing toward one another. This means may conveniently take the form of tongues or tabs extending upwardly from the sheet 10 and positioned between the 55 legs. Such tabs may be formed on the lower edge of each of the apertures 12, etc., in the side walls of the longitudinal members. For convenience, the tabs may be triangular in shape, as indicated at 37 in the drawings, although 60 other shapes may be found desirable. Furthermore, the tabs could be struck up from an intermediate portion of the tray bottom panel surfaces 27, 28, 29, to project between and be embraced by the side legs of the transverse members. Figure 6 clearly shows the function and 65 structure of the tabs 37.

When certain types of scores are used as fold lines on the blanks forming the transverse partition members, such as a perforated printer's 70 rule line, the folded blank will have a pronounced tendency to spring back to the flat position. In other words, the legs will have an inherent spreading tendency, and, in such cases, it will be unnecessary to provide means for preventing 75 the legs from collapsing toward one another.

Thus, the tabs or perforations 37 may be omitted. Such a construction is illustrated in the modified fragmentary views, Figures 7 and 8.

The cut-out corners 11 of the blank are provided to facilitate insertion and removal of a tray into and from a box. These cut-out portions have been found necessary because of the fact that the inside corners of the usual commercial candy boxes have a small mass or bunch of paper projecting into the interior of the box, 10 which tends to catch on the corner of a tray and prevent its ready removal. The cut-away corner portions of the tray provide a clearance space for this paper. In certain types of boxes, where this phenomenon is not present, it is unnecessary to provide the cut-out portions. 15

In the embodiment of the invention illustrated in Figure 9, the transverse partition members are of a cross-sectional shape and appearance which is dissimilar to the shape and appearance 20 of the longitudinal partition members. In this form the transverse members comprise a strip folded along a line 49 to provide two substantially contacting layers 41, 42. Thus, the transverse partition members have much less thickness than the first form of the invention, and, although this characteristic detracts from the appearance of the completed tray, it is desirable in some cases, such as for the purpose of increasing the useable area within the box. 25

When the tray of the present invention is used commercially, it is often found desirable to place two trays, one above the other, in a box of proper size, as illustrated in Figures 3 and 4. Each tray may hold a predetermined amount, such as one-half pound, of candy or other material, and the packaging of the material may thus be facilitated. Furthermore, the consumer of the candy may inspect the pieces in the lower tray by bodily removing the upper one, and the danger of spilling or 40 disarranging the candy in the upper tray is substantially prevented.

Although the invention has been described with considerable particularity in this specification, it must be understood that it is not limited to the details of construction illustrated, but comprehends all such modifications as fall within the scope of the appended claims or their equivalents. 45

We claim:

1. A partitioning tray for candy boxes and the like comprising a tray bottom panel, a longitudinal partition member having apertured sides, and a transverse partition member threaded through said apertures and disposed above the bottom panel and below the top of the longitudinal partition member, said longitudinal and transverse partition members being of substantially the same cross-sectional shape. 55

2. A partitioning tray for candy boxes and the like comprising a tray bottom panel, a longitudinal partition member having apertured sides, and a transverse partition member threaded through said apertures and disposed above the bottom panel and below the top of the longitudinal partition member, said transverse partition member having substantially vertical spaced side walls joined at their upper ends by a horizontal top wall of substantial width to impart substantial body and thickness to the transverse partition. 60

3. A partitioning tray for candy boxes and the like comprising a tray bottom panel, a longitudinal partition member having apertured sides, and a transverse partition member threaded through the apertures in the sides of the longitudinal member, disposed above the bottom panel 70

75

and below the top of the longitudinal partition member, said transverse partition member being of inverted, rectangular, U-shaped cross-section to impart substantial body and thickness to the transverse partition.

4. A partitioning tray for candy boxes and the like comprising a tray bottom panel, a longitudinal partition member having apertured sides, and a transverse partition member threaded through said apertures and disposed above the bottom panel and below the top of the longitudinal partition member, said longitudinal and transverse members each having substantially vertical side walls spaced substantially the same distance apart and being joined at their upper ends by a horizontal top wall of substantial width, to impart substantial body and thickness to the partitions formed by said members.

5. A partitioning tray for candy boxes and the like comprising a tray bottom panel, a longitudinal partition member having apertured sides, and a transverse partition member threaded through said apertures and disposed above the bottom panel and below the top of the longitudinal partition member, said longitudinal and transverse members each being of inverted, substantially U-shaped cross-section to impart substantial body and thickness to the partitions formed by said members.

30 6. A partitioning tray for candy boxes and the like comprising a tray bottom panel folded along longitudinal lines to provide upstanding integral longitudinal partition members of inverted substantially U-shaped cross section, the side walls of said partitioning members being apertured at spaced points between the tray bottom surface and the tops of the members, and transverse partition members of substantially the same cross-sectional shape as the longitudinal member threaded through said apertures therein to provide a plurality of compartments above the tray bottom panel defined by said longitudinal and transverse partitioning members.

7. A partitioning tray for candy boxes and the like comprising a tray bottom panel folded along longitudinal lines to provide upstanding integral, longitudinal partitioning members of inverted, substantially U-shaped cross-section, the side walls of said partitioning members being provided at spaced points with apertures extending substantially from the tray bottom surface to the undersurface of the tops of the members, and transverse partitioning members of similar cross-sectional shape threaded through said apertures and extending from the plane of the tray bottom substantially to the top of the longitudinal partitioning members to provide a plurality of compartments separated by similarly appearing longitudinal and transverse partition members of substantial thickness and body.

8. A partitioning tray for candy boxes and the like comprising a tray bottom panel folded along longitudinal lines to provide upstanding, integral, longitudinal partitioning members, the side walls of said members at spaced points being provided with rectangular apertures, and transverse partitioning members of inverted rectangular U-shaped cross-section threaded through said apertures in snug fit therewith, to provide a plurality of compartments above the tray bottom panel and defined by said longitudinal and transverse partitioning members.

9. A partitioning tray for candy boxes and the like comprising a tray bottom panel folded along longitudinal lines to provide an upstanding, in-

tegral, longitudinal partitioning member, the side walls of said member being provided with aligned rectangular apertures and a tab extending into each aperture from the lower edge thereof, a transverse partitioning member of inverted, rectangular U-shaped cross-section threaded through said apertures with the legs thereof embracing said tabs and being restrained against inward collapse by contact with said tabs, said longitudinal and transverse partitioning members serving to provide a plurality of compartments above said tray bottom panel.

10 10. A partitioning tray for candy boxes and the like comprising a sheet folded along parallel longitudinal lines to provide an upstanding substantially rectangular, inverted U-section, longitudinal partitioning member and tray bottom panels, the side walls of said member being provided with aligned apertures, and a transverse partitioning member threaded through said apertures and comprising a strip folded along parallel lines to substantially rectangular inverted U-section, said tray bottom panels being provided with tabs extending upwardly from the plane thereof between the legs of the transverse partition members to prevent inward collapse of the same, said longitudinal and transverse partitioning members serving to provide a plurality of compartments above said tray bottom panels.

15 11. A partitioning tray for candy boxes and the like comprising a sheet folded along longitudinal lines to provide upstanding integral longitudinal partitioning members having spaced side walls provided with aligned apertures, and transverse partitioning members having spaced side walls and being threaded through the aligned apertures to cooperate with said longitudinal members to divide the sheet into a plurality of compartments, said apertures each having an exterior outline corresponding to the exterior cross-sectional shape of the transverse partition members and having a projection extending into the interior of each of said transverse partition members in engagement therewith, to prevent collapse of the spaced side walls thereof.

20 12. A partitioning tray for candy boxes and the like comprising a tray bottom panel folded along longitudinal lines to provide up-standing, longitudinal partitioning members of inverted substantially U-shaped cross section, the side walls of said partitioning members being provided at spaced points with substantially rectangular apertures, and transverse partitioning members of inverted substantially rectangular U-shape threaded through said rectangular apertures to cooperate with the longitudinal members to divide the tray into compartments, the side walls of said transverse members having an inherent tendency to spread, whereby said walls engage the edges of said rectangular apertures and resist withdrawal.

25 13. A partitioning tray for candy boxes and the like comprising a tray bottom panel folded along longitudinal lines to provide up-standing longitudinal partitioning members of inverted, substantially U-shaped cross section, the side walls of said partitioning member being apertured at spaced points, and transverse partitioning members of substantially the same cross-sectional shape as the longitudinal members threaded through said apertures, and means carried by the transverse members engageable with the longitudinal members and adapted to resist displacement of the transverse members from assembled position.

14. A partitioning tray for candy boxes and the like comprising a tray bottom panel folded along longitudinal lines to provide up-standing, integral, inverted U-section longitudinal side members and similar longitudinal partitioning members, the inner faces only of the side members and the side faces of the partitioning members being apertured at spaced points, transverse partition members threaded through said apertures to cooperate with the longitudinal members to divide the tray into a plurality of compartments, and means on the ends of said transverse members projecting laterally beyond the apertures in the inner faces of said side members to prevent relative movement between the transverse members and the longitudinal and side members.
15. A partitioning tray for candy boxes and the like comprising a body member folded along parallel longitudinal lines to provide spaced tray bottom panels, longitudinal side spacing strips, and longitudinal partitioning members between the spaced tray bottom panels, said side strips and partition members being of inverted substantially rectangular U-section and having the vertical faces adjacent the tray bottom panels provided with aligned apertures at spaced points, in combination with inverted, folded transverse partition members threaded through said aligned apertures, the ends of the transverse members projecting outwardly through the apertures in the faces of the side members carrying means to prevent withdrawal of said ends through said apertures.
16. A partitioning tray for candy boxes and the like comprising a body member folded along parallel longitudinal lines to provide spaced tray bottom panels, longitudinal side spacing strips, and longitudinal partitioning members between the spaced tray bottom panels, said side strips and partition members being of inverted substantially rectangular U-section and having the vertical faces adjacent the tray bottom panels provided with aligned apertures at spaced points, in combination with transverse partition members threaded through said apertures, the ends of the transverse members projecting outwardly through the apertures in the faces of the side members being provided with laterally extending tongues adapted to prevent withdrawal of said ends through adjacent apertures.
17. A partitioning tray for candy boxes and the like comprising a body member folded along parallel longitudinal lines to provide spaced tray bottom panels, longitudinal side spacing strips, and longitudinal partitioning members between the spaced tray bottom panels, said side strips and partition members being of inverted substantially rectangular U-section and having the vertical faces adjacent the tray bottom panels provided with aligned apertures at spaced points, in combination with transverse partition members threaded through said aligned apertures, the ends of the transverse members projecting outwardly through the apertures in the faces of the side members being slotted and providing outwardly sprung tongues adapted to prevent withdrawal of said ends through the adjacent apertures.
18. A partitioning tray for candy boxes and the like comprising a main body member formed from a substantially rectangular blank and folded along longitudinal parallel lines to provide up-standing side bars and longitudinal partition members, the side faces of said bars and members being provided with aligned apertures at spaced points, in combination with transverse partition strips threaded through said aligned apertures, the four corners of the tray being cut away to provide a clearance space for the in-folded and bunched paper lining normally present in the corners of candy boxes, to facilitate removal of the tray from the box.
19. A partitioning tray for candy boxes and the like comprising a tray bottom panel, a plurality of longitudinal partition members integral therewith and having a plurality of aligned apertures extending therethrough, and a plurality of transverse partition members extending through said aligned apertures and each comprising vertically disposed side walls joined at their upper ends by a top wall, said vertical side walls being cut away on angular lines to provide a bevelled end to facilitate the entrance of said transverse partition members into said apertures during assembly of the parts.

HARRY E. JAMES.
